CLAIM

The ornamental design for a high branch pole, as shown and described.

DESCRIPTION

FIG. 1 is a front perspective view of the high branch pole, showing my new design;

FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 1;

FIG. 12 is a partial enlarged view of FIG. 1;

FIG. 13 is a partial enlarged view of FIG. 2;

FIG. 14 is a partial enlarged view of FIG. 2;

FIG. 15 is a partial enlarged view of FIG. 2;

FIG. 16 is a partial enlarged view of FIG. 2;

FIG. 17 is a partial enlarged view of FIG. 3;

FIG. 18 is a partial enlarged view of FIG. 3;

FIG. 19 is a partial enlarged view of FIG. 3;

FIG. 20 is a partial enlarged view of FIG. 3;

FIG. 21 is a partial enlarged view of FIG. 4;

FIG. 22 is a partial enlarged view of FIG. 4;

FIG. 23 is a partial enlarged view of FIG. 4;

FIG. 24 is a partial enlarged view of FIG. 4;

FIG. 25 is a partial enlarged view of FIG. 5;

FIG. 26 is a partial enlarged view of FIG. 5;

FIG. 27 is a partial enlarged view of FIG. 5;

FIG. 28 is a partial enlarged view of FIG. 5;

FIG. 29 is a partial enlarged view of FIG. 6;

FIG. 30 is a partial enlarged view of FIG. 6;

FIG. 31 is a partial enlarged view of FIG. 6; and,

FIG. 32 is a partial enlarged view of FIG. 6.

The dashed broken lines in the figures are for the purposes of illustrating portions of the high branch pole, and form no part of the claimed design. The dash-dot-dash lines are for annotating enlarged views, and form no part of the claimed design.

The dash-dot-dash lines are for an notating enlarged views, which form no part of the claim design.
